UNITED STATES PATENT OFFICE

2,413,158

DRIVING MECHANISM

William E. Van Dorn, Pasadena, Calif., assignor to
Preco Incorporated, a corporation of California

Original application July 9, 1940, Serial No.
344,509, now Patent No. 2,349,315, dated May 23,
1944. Divided and this application August 13,
1943, Serial No. 498,536

29 Claims. (Cl. 105—114)

1

This invention refers to improvements in driving mechanisms for accessories in transport vehicles. This application is a division of my co-pending application Ser. No. 344,509, filed July 9, 1940, which has issued on May 23, 1944, as Patent No. 2,349,315, entitled "Air circulating system for refrigerator cars and the like," and wherein the subject-matter driving mechanism is shown as driving an air impelling device. Said co-pending case is now directed to the air circulating devices regardless of the particular mechanisms by which they are driven; this present application is directed to the driving mechanisms regardless of the character of the device driven.

The general purpose of the present invention is the provision of driving mechanism, obtaining its power normally from a car running gear, which is easily applicable to cars of all types and kinds, has high efficiency of operation, freedom from necessity of frequent servicing, ease of servicing, and which is easily and quickly adaptable to being driven either from the running gear of the car or from an independent power source. Further objectives and the corresponding characteristics and features of the invention will best be gathered from the following description of illustrative forms of the invention. For that purpose reference is had to the accompanying drawings in which:

Fig. 1 is a fragmentary transverse section showing one form of my improved drive mechanism applied to a refrigerator car and driving an air impeller, this view being taken as indicated by line 1—1 on Fig. 2;

Fig. 2 is a longitudinal section and side elevation of the parts shown in Fig. 1, being taken in the aspect indicated by line 2—2 of Fig. 1;

Fig. 3 is a fragmentary section taken on line 3—3 of Fig. 1;

Fig. 4 is a detail section taken on line 4—4 of Fig. 1;

Fig. 5 is an enlarged detail section taken on line 5—5 of Figs. 2 and 4;

Fig. 6 is a diagrammatic section taken as indicated by line 6—6 on Fig. 3;

Fig. 7 is a section similar to that of Fig. 6 and showing a modified form of traction roller for the driving mechanism;

Fig. 8 is a transverse section, similar in aspect to the transverse section of Fig. 1, and taken as indicated by line 8—8 on Fig. 9, showing a modified form of driving mechanism;

Fig. 9 is a fragmentary longitudinal section taken on line 9—9 of Fig. 8;

2

Fig. 10 is a longitudinal section taken on line 10—10 of Fig. 8;

Fig. 11 is an enlarged detail section in a substantially horizontal plane taken on line 11—11 of Fig. 10;

Fig. 12 is an enlarged detail section taken on line 12—12 of Fig. 9;

Fig. 13 is an enlarged transverse section taken as indicated by line 13—13 on Fig. 2 and showing 10 the application of the independent driving motor;

Fig. 14 is a section taken as indicated by line 14—14 on Fig. 13.

The drawings illustrate the driving mechanisms as applied to the driving of an accessory

15 which is here shown illustratively as an air impeller unit, a fragment of which is shown at 30 in Fig. 1. The unit need not here be particularly described, as it is intended to typify any car accessory which can be driven by the driving

20 mechanisms. As illustrated, the particular accessory is driven by a shaft 40 which extends transversely over the car floor 20 and is here shown as extending outwardly beyond the inner surface of car wall 21. Also, as particularly

25 shown here, for the easy application of the mechanisms to existing cars, the shaft extends outwardly through the car wall and the driving connections to it are shown as being external of the car wall. A shaft such as 40 projects into or

30 through the car wall, a tubular liner 57 may be used and the annular space between the shaft and liner may be sealed by some suitable means such as the series of disks, indicated at 58, alternately attached to the shaft and the liner. And,

35 as here shown, the outer end of shaft 40 carries a pulley 60 adapted to take a driving V-belt 61. Pulley 60, as shown better in detail in Fig. 13, has an outer screw-threaded hub 62 adapted to take another pulley 63 for the independent motor

40 drive which may be applied to shaft 40 when the car is not in motion, as will be described.

However, as will become clear from the succeeding descriptions of the driving mechanisms, although they are particularly well adapted to driving a shaft which is disposed transversely of the car, they are inherently not limited to driving a shaft in that disposition nor in the particular disposition which is here illustratively shown.

In the form of driving mechanism shown in 50 Figs. 1 to 7, a transverse tubular mounting shaft 65 is mounted directly under the car floor with its inner end rotatably carried in a bracket 66 conveniently mounted on one of the longitudinal girders 67 of the car body. The outer end of 55 mounting shaft 65 is rotatably carried in a brack-

et plate 68 secured to the under side of the car body in a position here shown as substantially flush with the outer side of the car wall. Just inside the bracket plate 68 an arm 69 is mounted at its upper end loosely around mounting shaft 65, so that although that end of arm 69 is thus restricted to a swinging motion, it is to a certain extent allowed universal swinging motion. Arm 69 extends diagonally downwardly and at its other end is attached, preferably rigidly, to the outer end of the tubular shaft housing 70. A brace 69a is placed between housing 70 and arm 69. The purpose of this rigid, braced attachment is to enable arm 69, which is confined longitudinally at shaft 65—see Fig. 5—to confine the shaft housing 70 against any substantial movement longitudinal of itself. The inner end of shaft housing tube 70 has a pair of opposite perforated lugs 71 through one of which there extends the bent end 72 of an arm 73 rigidly mounted at its other end on mounting shaft 65. In its normal or average operating position the shaft housing 70 is preferably substantially parallel to mounting shaft 65. The lug 71 which is shown as unused in Figs. 1 and 3 is provided for use when the mechanism is set up at the end of the car opposite to that which is here being described.

Driving shaft 75 is carried in bearings 76 in tubular housing 70, the bearings taking end thrust as well as radial loads. At its outer end this shaft carries drive pulley 77 which aligns with pulley 60 and takes the V-belt 61. At its inner end the extended end of shaft 75 carries the hub 78 of traction roller 79. This traction roller, whose structure and form will be hereinafter explained in detail, carries an external traction tire 80 of rubber or any other suitable material adapted to be frictionally driven by the periphery of car wheel 81. Specifically I show the driving mechanism as driven immediately from the car wheel, as it presents the most convenient driving member associated with the running gear or car axle. The car wheel typifies any suitable driving element associated with the running gear.

To keep traction roller 79 in pressure contact with the car wheel, and also to put the desired traction tension on belt 61, a yielding pressure is exerted on shaft housing 70 at a point between traction wheel 79 and pulley 77, the spacing of the pressure application point between pulley 77 and traction wheel 79 determining the proportionate applications of the pressure to those respective members. As shown in the drawings, a coil spring 82, coiled about mounting shaft 65, is conveniently used for the purpose, the free end 83 of the spring pressing downwardly upon housing 70 at the chosen position, which is here shown as being closer to roller 79 than to pulley 77. The fixed end 84 of the spring (see Figs. 2 and 4) bears upwardly in a notch 85 in the lower end of an angle plate 86 which is secured to the bracket plate 68.

This angle plate 86 also has a vertical slot 87 in which handle 88 may be raised and lowered. The normal position of handle 88 is its lower position as shown in the drawings, but it may be raised and held in its upper position, shown in dotted lines in Fig. 2, by a pin 89 which may be inserted in the plate 86. The handle 88 has a loop 90 at its inner end loosely surrounding the mounting shaft 65, or the extension thereof which is formed by the stud 65a. A collar 91 surrounds shaft 65 and carries a lug 92. The collar, tubular shaft 65 and shaft stud 65a are all secured together and lug 92 is positioned appropriately, by

5 a pin bolt 93. A head 65b which lies outside the bracket plate 68, acting in conjunction with the fixed collar 91 and the parts 69 and 90, limits longitudinal (axial) movement of shaft 65 and of the mounting arm 69. In the normal operating 10 positions of the parts lug 92 is in such position that handle 88 lies below it with a sufficient clearance to allow the driving shaft 75 and traction wheel 79, and mounting shaft 65, the necessary amount of motion about the axis of shaft 65 for normal operation, without lug 92 coming into contact with handle 88. Such relation of the parts is shown in Fig. 4. The purpose of handle 88 is to facilitate the lifting and hanging up of 15 drive shaft 75 to disconnect the driving train between car wheel 81 and driven shaft 40. Lifting either or both ends of shaft 75 would break the driving connection; it is here shown as being broken at a single point by lifting the inner end 20 of shaft 75 and traction roller 79.

When handle 88 is raised it comes into contact with lug 92 and rotates mounting shaft 65 in a clockwise direction in Figs. 2, 3 and 4. Arm 73 is correspondingly swung upwardly, lifting the inner end of shaft housing 70 and lifting traction roller 79 off car wheel 81. In this operation the outer ends of housing 70 and the driving shaft 75, and pulley 77, are not moved except to tilt them slightly about a transverse axis which is determined by the center point of pulley 77 (in the position in which it is supported by belt 61) and, loosely, by the center point of the loose mounting of arm 69 on shaft 65. The axis referred to is transverse of shaft 75. The parts can 35 be locked in the raised position by use of pin 89, and traction roller 79 may then rotate freely to accommodate the independent power driving of the system, afterwards described.

The casing which encloses the belt drive and 40 affords a mounting for the independent motor drive, is made up essentially of a removable cover plate 95, and an upper end wall 96 and side walls 97 which are preferably formed of a single piece of metal of Z-section cut and bent at the corners 45 at 98. The rear flanges 99 of the Z-section are secured to the car wall and to bracket plate 68. The cover plate 95 has inturned flanges 100 along its longitudinal edges adapted to engage the outer flanges 101 of the side walls. The lower end of 50 the cover plate is bent inwardly and then upwardly as shown at 102 in Figs. 1 and 2 to form a protective casing below the drive pulley 77; and bolts or pins 103 hold the cover in place. The cover may be easily removed by removing the 55 bolts 103 and sliding the cover downwardly. Details of formation of the casing and its cover plate may be seen more readily in the horizontal sections of Figs. 12 and 14. Although Fig. 12 is 60 illustrative of the modified form of driving mechanism, the casings for both forms of the mechanisms may be the same and have therefore been given the same numerals in Fig. 12. The drawings show how the belt drive is arranged in a plane parallel and close to the car wall, and the 65 enclosing casing is flat and shallow, projecting only a small distance from the wall.

Opposite the upper drive pulley 60 cover 95 has 70 an opening 105 to facilitate attachment of the independent drive pulley 63. This pulley, as shown in Fig. 13, has an internally threaded hub 106 adapted to be threaded onto the threaded hub 62 of pulley 60. The direction of threading pulley 63 onto hub 62 is the same as the direction of drive by the independent drive motor M. Motor M has a drive pulley 107 of suitable size, and

belt 108 drivingly interconnects pulley 107 with pulley 63. Motor M is mounted at its pulley end on a bracket 109 which has inturned flanges 110 forming sliding guides for the bracket and motor on the longitudinal edges of cover plate 95. Set-screws 111 may be used instead of one of the flanges, so that by retracting the set screws the motor bracket may be removed from the casing cover without having to slide it vertically over the end of the cover. Although other temporary mountings for the independent drive motor may be used, the described mounting has certain advantages in ease and quickness of motor application, and in the fact that the motor is so mounted on the car that it may move gravitationally to tighten its own drive belt.

Whenever it is desired to drive the impeller unit from the independent motor M, it and the pulley 63 and belt 108 are put in place as shown in Figs. 13 and 14. Handle 88 is raised to the dotted line position in Fig. 2, and locked in that position. Raising the handle 88 rotates arm 73 about mounting shaft 65 and thus raises the traction roller 79 off car wheel 81. In this operation only that end of shaft housing 70 which is adjacent friction roller 79 (the left-hand end in Fig. 1) is raised. The other end of shaft housing 70 is allowed to remain substantially in the position of Fig. 1 by reason of the looseness of arm 69 at its mounting on mounting shaft 65. Thus the drive belt 61 is not disturbed by raising traction pulley 79, but remains at all times in proper contact with the two drive pulleys 60 and 77. If the outer end of shaft 65 and pulley 77 were also raised it would be necessary to employ some means of keeping the belt in alignment with the pulley to insure their reengagement when the pulley is subsequently lowered.

It is preferred that the independent motor drive be applied directly to the upper impeller unit shaft, as has been described. But it may be applied to the lower driving shaft, such as the shaft 75 that has been described, for the driving belt 61 is always in tractive relation to its two pulleys.

In certain aspects of my invention, for instance those relating to the independent driving of the impeller unit, the normal drive from the running gear may be had in any suitable manner. I prefer however to take that drive by friction traction from a wheel or similar member on the running gear, and certain aspects of the invention relate to driving mechanism for that purpose. In that connection the wheel illustrated at 81 in the drawings may represent any wheel on the running gear. Preferably however it is the car supporting wheel, and further features of the invention have to do with utilizing traction drive from that wheel.

In the form of driving mechanism which has so far been described, the whole mechanism is mounted upon the car body, and a certain amount of relative lateral movement takes place between car wheel 81 and traction roller 79 when the truck swivels with relation to the car body in rounding curves, or shifts laterally with respect to the body. Figs. 6 and 7 show how the lateral component of the relative movement between car wheel and body is accommodated.

Referring first to Fig. 6, the tread of the car wheel is shown at 81a and its flange at 81b. The rubber or other tire 60 of the traction roller is made with tapering side surfaces 79a and preferably with a flat outermost peripheral surface 79b. The general sectional shape of the tire may

be described as outwardly tapering, and preferably with a flat outermost periphery so as to provide a fairly broad traction surface for engagement with wheel tread 81a in normal operation. In normal operation, on straight-away track, the traction roller 79 occupies a relative position somewhat like that shown in Fig. 1 and shown at position A in Fig. 6. Relative movement of the traction roller to the left (or the wheel 81 to the right) in Fig. 6 will cause its left-hand tapered surface 79a to climb wheel flange 81b to the relative position shown at B, and further relative movement of the traction roller toward the left makes the traction roller reach the relative position shown at C where its right-hand tapered wall 79a is riding the inner surface of the wheel flange. On return movement toward position A the roller will climb the flange. In all these relative positions the traction roller is in frictional driving engagement with either the car wheel tread or the flange. And on relative movement of the traction roller toward the right in Fig. 6, it may move relatively as far as the position shown at D, where its lefthand tapered surface is still in frictional driving contact with the edge of the wheel tread. On return movement toward position A the lefthand tapered surface 79a will climb the outer edge of the wheel.

In the arrangement which is shown in Fig. 6, traction wheel 79 is prevented from dropping below the position D, in case it should pass further relatively to the right, by the lug 92 (see Fig. 4) engaging handle 88, acting as a limiting stop to the downward movement of the traction wheel. Thus if the roller should under any circumstances pass further relatively to the right than position D, it will always be held at such a level relative to wheel tread 81a that upon reengaging the wheel tread it can climb back to position A. The traction roller may thus at times go out of driving contact momentarily when the car is rounding short curves, but it will immediately move back into proper driving contact as the car passes beyond such a curve. The freedom which is allowed the traction wheel in a direction radial of the car wheel, allows the traction wheel to climb and descend the whole tread and flange contour of the car wheel.

In the arrangement shown in Fig. 6 the relative position C is substantially the limiting position of the traction roller toward the left. By choosing the normal relative position to be substantially that shown at A, it is found that ample relative latitude of movement is allowed without the roller having to reach or pass beyond the position C in its relative movement toward the left. And, as before stated, it may pass beyond its relative righthand position D without any harm.

To allow the roller to pass beyond its relative right-hand position shown at D in Fig. 6, without losing driving contact with the car wheel, the arrangement shown in Fig. 7 may be used. Here the tread body of the traction roller 79c is the same as before described, but it has at its left-hand end a cylindric extension 79d, which may be composed of the same substance as the tread. The diameter of this extension is such that its periphery clears wheel flange 81b when the roller tread 79b is riding on the wheel tread 81a. The length of cylindric extension 79d is such that when the roller reaches such a relative position as shown at D in Figs. 6 and 7, the periphery of 79d will then ride on the wheel tread; but in lowering to the position D the end of extension

79d will clear the wheel flange. With 79d riding the wheel tread the traction roller may then move further out relatively toward the right without losing tractive engagement. The extension 79d also performs the office of limiting the downward movement of the traction roller in its extreme righthand position, and the limiting function of lug 92 may then either be eliminated, or arranged to act as a safety limit in the position of the traction roller below that shown at D.

Further, such a traction roller may also have an opposite cylindric extension such as shown at 79e in Fig. 7 which will ride the periphery of flange 81b if the traction roller passes further relatively to the left than shown at C in Fig. 6.

In the swivelling movement between the car body and truck there is also a relative movement component in a longitudinal direction, between the car body and any wheel mounted on the truck axle except at the center. That relative longitudinal movement, as well as vertical movements of the body relative to the wheel, are taken care of by the action of spring 82, and the swinging action of arm 73, keeping the traction wheel in contact with the car wheel.

It will be seen from Fig. 3 that in normal position the radial line R, drawn through the centers of shafts 65 and 75, is approximately tangent to a circle concentric with car wheel 81. Swinging motion of traction wheel 79 about shaft 65 is therefore substantially radial of wheel 81. And when wheel 81 moves relatively longitudinally, traction roller 79 swings (in Fig. 3) up and to the left or down and to the right; and the angularity of radius R and the length of arm 73 are such that in all its positions the spring pressed swinging movement of the traction roller is approximately radial of wheel 81.

These described movements of traction wheel 79 and the inner end of drive shaft 75 and housing 70 are allowed by the universally loose mounting of their outer ends, at the mounting of supporting arm 69 on mounting shaft 65. Preferably in normal position driving shaft 75 is substantially parallel to shaft 65, and the loose mounting of arm 69 allows all the necessary oscillations of the inner end of shaft 75 about its normal position. In this preferred arrangement the length of arm 69 is substantially parallel to the radial line R of Fig. 3; and the direction of length of arm 69 is, as shown in Fig. 2, transverse of the direction between drive shaft 75 and impeller shaft 40, so that the downward swinging movement of arm 69 tightens belt 61. For that reason, as well as the fore-and-aft location of the impeller unit in the car body, the direction of shaft 40 from shaft 75 is angled somewhat from the vertical in the relative direction shown in Fig. 2—away from a vertical plane through the center of wheel 81.

It has previously been noted that when the inner end of shaft 75 and its traction roller 79 are raised, the whole shaft assembly tilts about a transverse axis which passes through the approximate center point of pulley 77 at the outer end of the shaft and approximately through the center of the loose universal mounting of arm 69 on mounting shaft 65. The tilting movements of shaft 75 due to relative movements of car wheel 81 in operation, are the same. One point on the tilting axis lies approximately at the center point of pulley 77, with the position of the pulley fixed by the length of belt 61 and by the fact that spring 82 keeps the belt in uniform tension. The function of spring 82, insofar as movements of

the outer end of shaft 75 and of pulley 77 are concerned, is merely to keep tension on the belt and to adjustably move those parts to accommodate differences or changes in belt lengths. In any given adjusted operating condition the center of pulley 77 is an approximately fixed point. The other point which fixes the tilting axis of shaft 75 is a point which more or less closely coincides with the center point of the loose mounting of arm 69 on mounting shaft 65. Thus the tilting axis is one which, as viewed in Fig. 3, approximately coincides with radius R. And as viewed for instance in Fig. 1, it is seen to lie in a plane transverse of and nearly at right angles to shaft 75, and therefore to lie substantially in the plane of the two pulleys and their belt.

The general functions of the mounting of shaft 75 may be described as follows. The inner end of the shaft with its traction roller 79 is supported so as to be constrainedly movable along a line of movement to and from the car wheel. The outer end of the shaft is supported so as to be capable of adjustment to and from pulley 60 to keep belt 61 taut. Spring 83 holds the outer end of shaft 75 and pulley 77 in the proper adjusted position and swings the inner shaft-end and roller 79, about a transverse axis at the outer shaft-end, to follow the relative movements of car wheel 81.

The arrangement and mounting of the traction roller that have so far been described have been found to allow sufficient movement between the car wheel and body for relatively short cars travelling existing railway curves. For relatively long cars, where the angular swivelling movement between car body and truck is greater, and with trucks employing swing hangers for lateral motion, it may be preferred to use the form of driving mechanism which is now to be described. This modified form of driving mechanism is shown particularly in Figs. 8 to 12. The impeller unit or other accessory, its drive by the pulley 60, and its drive by independent drive motor M, are the same as before described.

In Fig. 8 the numeral 20 again designates the car floor and 81 the car wheel. Numeral 120 designates a part of the truck frame. The impeller unit or other accessory which is driven by the mechanism shown in Fig. 8 is assumed, for purposes of description, to be the same as before described, the belt 61 of Fig. 8 driving the impeller unit in the same manner. The casing enclosing the belt drive is made up in substantially the same manner as has been described.

A tubular bearing member 121 is mounted on brackets 122 which are for convenience mounted upon a mounting plate 123 that is welded to truck frame 120. A carrier shaft 124 is rotatable in bearing sleeve 121 and carries a radial arm 125 at its end adjacent car wheel 81. The outer end of this arm carries a bearing housing 126 within which there is an annular rubber or similar sleeve 127 in which the ball bearing 128 is carried. The outer race ring of the ball bearing is recessed into the inner surface of ring 127 as shown at 129, and that recessing enables the bearing to resist end thrust to a sufficient extent, although the bearing is free to take proper alignment to the extent that is necessary in the operation of the device. Bearing 128 carries a hub sleeve 130 through which the non-circular shaft 131 has slidable driving engagement. Traction roller 132 with its tread 133 is mounted on hub sleeve 130. Tread 133 is preferably of rubber or some good traction material and has a broad tread face

which is made slightly conical to conform to the slightly conic shape of car wheel tread 81a. A coil spring 135 surrounds bearing tube 121 with its stationary end 136 bearing upon the mounting plate 123, and its moving end 137 hooks over the arm 125 to force the arm and the traction wheel toward the car wheel.

A handle 138 has its inner end 139 loosely mounted about mounting shaft 124, and is loosely held in place on the shaft by a collar 140. Collar 140 carries a handle engageable lug 141 in such a position as to allow sufficient angular movement of shaft 124 to accommodate normal movement of the traction roller in following the car wheel. The swinging movements of arm 125 to make roller 132 follow the wheel are, in this design, relatively small. Other than to accommodate wear, substantially the only movements of roller 132 are those due to relatively vertical movement between the wheel and truck and those due to the longitudinal component of swivelling movements. And those due to the latter movements are again comparatively small because bearing 128 is close to roller 132. The traction roller may be raised off the car wheel by elevating handle 138, and may be held in that position by inserting pin 142 behind the handle.

The other end of shaft 131, as shown more clearly in detail in Fig. 12, carries a bushing sleeve 145, which in turn is carried by the ball bearing 146. Bushing sleeve 145 carries lower drive pulley 77a. Bearing 146 has its outer race recessed at 147 into the inner face of an annular rubber element 148 which is carried in a bearing housing 149 mounted on the outer end of an arm 150 whose inner end is rigidly mounted on a sleeve 151 rotatable upon pivot pin 152. Pivot pin 152 is mounted between the flanges of a U-shaped bracket 153 which is mounted, by welding or otherwise, on a bracket plate 154 which in turn is mounted, as by welding, on the under frame 155 of the car. The mounting of both the bearing carrying arms, and the mountings of the bearings in those arms, are such as to restrict drive shaft 131 against endwise displacement.

A coil spring 156 surrounds sleeve 151 and has its fixed end 157 passing through a lug 158 which is mounted on the mounting bracket 152 (see Fig. 9). The free end 159 of the spring bears against bearing housing 149 in such a direction as to tend to swing arm 150 and the bearing housing and that end of shaft 131 downwardly and to the right in Fig. 9. The radial length of arm 150 is transverse of the direction of belt drive 61 so that the action of spring 156 is to tighten the belt. And, due to the freedom which is accorded both bearings 146 and 128 to aline themselves with shaft 131, spring 156 acts to keep the righthand end of shaft 131 in its illustrated position, and to keep belt 61 tight, when the lefthand end of shaft 131 moves to keep the traction roller in wheel engagement, or when the lefthand end of shaft 131 with traction wheel 132 are raised away from the car wheel.

In this latter described form of driving mechanism the traction roller 132 always occupies substantially the same position with relation to the car wheel, as regards lateral movement. Being carried by the truck frame, the traction roller has substantially no lateral movement relative to the car wheel. Lateral motion of the traction roller with relation to the car body is taken up by the sliding motion of drive shaft 132 through hub sleeve 130. And all other relative motions between the car body and truck are allowed by the

universal freedom of shaft 131 to take, within the necessary limits, any relatively angled position that may be required. Traction roller 132, due to this type of mounting, keeps in tractional contact with the wheel tread regardless of the angle through which the truck and wheel may swivel with relation to the car body. This form of driving mechanism is therefore universally applicable, and is particularly applicable to long cars where the angles of swivelling action are large, and to trucks incorporating swing hangers for lateral motion.

A short analytic summary of the accommodation movements of the traction rollers and driving shafts, in both forms of the driving mechanism may be helpful to understanding certain features of the invention. In both forms the inner end of the drive shaft and the traction roller are, with regard to movements in a plane longitudinal of the car or truck, restricted to movement which is substantially radial of the car wheel; that is, a movement which has at least a substantial component radial of the car wheel. This restriction is, specifically, performed by swinging arm 69 in the first form, 125 in the second form.

The outer ends of both drive shafts are so mounted that, with some outer point stationary (e. g. the axial center of power take-off pulley 77 or 77a), the outer end may swing about that point in the plane of movement of the inner end and of the traction roller. Disregarding for the moment the movement of the outer shaft end which is desirable for keeping the driving belt tight (and which would be unnecessary if for instance the power were taken off the drive shaft through gears or by a flexible shafting), the movements so far noted are, in substance, the only ones which are necessary to the drive shaft of the first form. In the first form the last mentioned swinging movement is accommodated by the loose or universal mounting of bracket arm 69 about mounting shaft 65; in the second form, by the universal mounting of bearing 146. Translational movement of the outer shaft ends (except in the direction desirable for the belt drive) is restricted by the carrying arms 69 and 150.

In the first described form the inner end of the drive shaft is also restricted against movement longitudinal of the shaft, transversely of the plane in which its radial movement takes place. In that form the restriction is specifically the result of the fact that the shaft carrying arms are mounted on the car body; while in the second form there is no corresponding restriction of relative longitudinal movement of the shaft inner end and of the traction roller, the shaft carrying arm 125 moving with the truck.

In both forms of the drive mechanism the outer shaft end also has, in addition to its swinging freedom previously referred to, a freedom to move in a direction which tightens the take-off belt. The direction of that movement depends on the orientation of the belt. In the designs of both forms, as illustrated here, that orientation is near enough to parallelism with the radial movement of the inner end of the shaft that the belt tightening movement of the outer end can be, and in the first form is, substantially parallel to the movement of the shaft's inner end. And in the first described form that fact is taken advantage of in the very simple form of shaft carriage which embodies the preferred

mounting of both arms 73 and 69 on the same mounting shaft 65.

It has been mentioned that the drawings show the driving mechanisms in their design and arrangement as they are preferably applied to existing cars. On most existing cars there is sufficient room between the external surface of the car wall and the so-called "clearance line" to accommodate those parts of the driving mechanism that are here described as being located outside the outer surface of the car wall. And in applying the mechanisms to existing cars it is more convenient to place them external of the wall. However, the wall may be recessed to receive the upper parts of the drive mechanism; or the driving belt may even be run up through the car floor interiorly of the normal car wall and housed by an interior housing which may be regarded as an inward recessing of the car wall to a depth greater than the normal wall thickness. Such arrangements may be more easily applied to cars that are designed particularly to take my mechanisms, but they may also be applied to existing cars if desired or necessary. In any such arrangement the recessed wall may be regarded as the car wall for the purpose of my invention and the definition of certain of its aspects in the following claims. Other aspects of the invention, such as those having to do with the impeller unit in itself or the lower driving mechanisms, will be understood to be not necessarily limited to any location relative to the car wall.

I claim:

1. In a car-body-mounted mechanism adapted to be driven from a flanged car wheel, a tractive driving roller adapted to engage the periphery of the car wheel, means for mounting the roller on the car body in the longitudinal vertical plane of the car wheel and in normal tractive engagement with the car wheel tread, the tractive roller having a wheel engaging tread with an annular beveled face at its side which is toward the car wheel flange, and having a substantially cylindric extension beyond the beveled face, said extension being of a diameter sufficiently less than that of the roller tread to clear the car wheel flange when the roller tread engages the car wheel tread.

2. A tractive driving roller as specified in claim 1, and also including an element associated with the side of the roller opposite the side mentioned and adapted to support the roller by contact with the car wheel flange.

3. In a car-body-mounted mechanism adapted to be driven from a flanged car wheel, a tractive driving roller adapted to engage the periphery of the car wheel, means for mounting the roller on the car body in the longitudinal vertical plane of the car wheel and in normal tractive engagement with the car wheel tread, the tractive roller having a wheel engaging tread with an annular beveled face at its side which is toward the car wheel flange, and having a substantially cylindric extension beyond the beveled face, said extension being of a diameter sufficiently less than that of the roller tread to clear the car wheel flange when the roller tread engages the car wheel tread, and said extension being of a length not greater than the width of the car wheel tread.

4. In a car structure having a body and running gear including a wheel and axle element; driving mechanism for an accessory which is carried by the car body and which has an operating shaft; said driving mechanism including, a driving shaft extending transversely of the car body,

a belt and pulley driving connection between the accessory operating shaft and one end of the driving shaft, a traction roller associated with the other end of the driving shaft and adapted to be pressed into tractive engagement with the wheel and axle element, and mounting means for the driving shaft on the car structure including a pair of spaced bearings for the shaft, a pair of arms independently pivotally connected each at one end to the car structure and supportingly connected to the shaft bearings at their other ends, at least one of said connections of each arm being capable of allowing universal swivelling movement, and yielding means acting to move the driving shaft about the arm pivots in a direction toward the wheel and axle element and away from the accessory shaft.

5. In a car structure having a body and running gear including a wheel and axle element; driving mechanism for an accessory which is carried by the car body and which has an operating shaft; said driving mechanism including, a driving shaft extending transversely of the car body, frictional driving connections acting directly between the wheel and axle element and one end of the driving shaft and between the accessory shaft and the other end of the driving shaft, said frictional driving connections adapted to be put in tractive driving engagement by movements of the respective ends of the driving shaft in predetermined directions transverse of the shaft length, mounting means for the shaft on the car structure including a pair of spaced bearings for the shaft, a pair of arms independently pivotally connected each at one end to the car structure to swing independently in planes transverse of the shaft length, and said arms being supportingly connected to the shaft bearings at their other ends, at least one of said connections of each arm being capable of allowing universal swivelling movement, and yielding means acting to move the two ends of the driving shaft about the arm pivots in said predetermined directions.

6. Driving mechanism as defined in claim 4, and also including manually operable means for moving at least one end of the driving shaft in a direction opposite to that stated so as to render ineffective the driving connection at that end of the shaft.

7. Driving mechanism as defined in claim 5, and also including manually operable means for moving at least one end of the driving shaft transversely in a direction opposite to said predetermined direction so as to render ineffective the driving connection at that end of the shaft.

8. In a car structure having a body and running gear including a wheel and axle element; driving mechanism for an accessory which is carried by the car body and which has an operating shaft; said driving mechanism including, a driving shaft extending transversely of the car body, a belt and pulley driving connection between the accessory operating shaft and one end of the driving shaft, a traction roller associated with the other end of the driving shaft and adapted to be pressed into tractive engagement with the wheel and axle element, and mounting means for the driving shaft on the car body including, a pair of spaced bearings for the shaft, a pair of arms independently pivotally connected each at one end to the car body and supportingly connected to the shaft bearings at their other ends, at least one of said connections of each arm being capable of allowing universal swivelling movement, and yielding means acting to move the

driving shaft about the arm pivots in a direction toward the wheel and axle element and away from the accessory shaft.

9. In a car structure having a body and running gear including a wheel and axle element; driving mechanism for an accessory which is carried by the car body and which has an operating shaft; said driving mechanism including, a driving shaft extending transversely of the car body, a belt and pulley driving connection between the accessory operating shaft and one end of the driving shaft, a traction roller associated with the other end of the driving shaft and adapted to be pressed into tractive engagement with the wheel and axle element, and mounting means for the driving shaft including a transverse mounting shaft rotatably supported on the car body, a mounting bearing for the first mentioned end of the driving shaft, an arm swivelly pivoted at one end substantially concentric with the 10 mounting shaft and extending from its pivot to carry said mounting bearing at its free end, a mounting bearing for the other end of the driving shaft, an arm mounted at one end on the mounting shaft for rotation therewith and extending from that shaft to carry the last mentioned bearing at its free end, means connected to the mounting shaft to raise the last mentioned arm and its associated bearing, and yielding means acting to depress both said mounting bearings.

10. In a car structure having a body and running gear including a wheel and axle element; driving mechanism for an accessory which is carried by the car body and which has an operating shaft; said driving mechanism including, a driving shaft extending transversely of the car body, a belt and pulley driving connection between the accessory operating shaft and one end of the driving shaft, a traction roller associated with the other end of the driving shaft and adapted to be pressed into tractive engagement with the wheel and axle element, and mounting means for the driving shaft on the car body including a transversely extending rigid mounting member on which the driving shaft is journaled, a mounting arm rigidly connected at one of its ends with one end of said mounting member and universally pivoted at its other end on the car body, another mounting arm universally connected at one of its ends with the other end of said mounting member and pivoted at its other end to the car body, and yielding means acting to move the mounting member and the driving shaft about the arm pivots in a direction toward the wheel and axle element and away from the accessory shaft.

11. In a car structure having a body and running gear including a wheel and axle element; driving mechanism for an accessory which is carried by the car body and which has an operating shaft; said driving mechanism including a driving shaft, mounting means for the driving shaft on the car body including a rigid mounting member on which the driving shaft is journaled near its ends, a mounting arm rigidly connected at one of its ends with one end of the mounting member and universally pivoted at its other end on the car body, another mounting arm universally connected at one of its ends with the other end of the mounting member and pivoted at its other end to the car body, power transmission connection between the wheel and axle element and one end of the driving shaft, and power transmitting connection between the other

end of the driving shaft and the accessory shaft.

12. In a car structure having a body and running gear including a wheel and axle element; driving mechanism for an accessory which is carried by the car body and which has an operating shaft; said driving mechanism including a driving shaft, mounting means for the driving shaft on the car structure including a rigid mounting member on which the driving shaft is journaled near its ends, a pair of arms independently pivotally connected each at one end to the car structure and supportingly connected at their other ends to the mounting member near its ends, at least one of said connections of each arm being capable of allowing universal swiveling movement, power transmission connection between the wheel and axle element and one end of the driving shaft, and power transmitting connection between the other end of the driving shaft and the accessory shaft.

13. In a car structure having a body and running gear including a wheel and axle element; driving mechanism for an accessory which is carried by the car body and which has an operating shaft; said driving mechanism including, a driving shaft extending transversely of the car body, a belt and pulley driving connection between the accessory operating shaft and one end of the driving shaft, a traction roller associated with the other end of the driving shaft and adapted to be pressed into tractive engagement with the wheel and axle element, and mounting means for the driving shaft including a transverse mounting shaft rotatably supported on the car body, a transversely extending mounting tube surrounding the driving shaft and within which tube the driving shaft is journaled, an arm swivelly pivoted at one end substantially concentric with the mounting shaft and extending from its pivot to carry one end of the mounting tube, an arm mounted on the mounting shaft for rotation therewith, extending from that shaft, and swivelly carrying the other end of the mounting tube, means connected to the mounting shaft for rotating it to raise the last mentioned arm, and yielding means bearing downwardly on the mounting tube at a point between the ends of the driving shaft.

14. In a car structure having a body and running gear including a truck frame and a wheel and axle element; driving mechanism for an accessory which is carried by the car body and which has an actuating shaft; said driving mechanism including, a drive shaft, a bearing mounting for one end of the shaft supported on the car body and constrainedly movable with relation to the car body along a line of movement to and from the accessory shaft, and a bearing mounting for the other end of the shaft also supported on the body and constrainedly movable along a line of movement to and from the wheel and axle element, the two ends of the driving shaft being independently movable along said lines of movement, power transmitting elements adapted to transmit power from the wheel and axle element to the second mentioned end of the driving shaft and from the first mentioned end of the driving shaft to the said accessory shaft, each of which power transmitting means is rendered effective by movement of the respective end of the driving shaft in one direction along the respective line of movement, and means normally urging the two ends of the driving shaft in the directions stated.

15. Driving mechanism as defined in claim 14,

15

and in which the power transmitting elements are, respectively, a traction roller mounted on the second mentioned end of the driving shaft, and a belt and pulley transmission element connecting the first mentioned end of the driving shaft to the accessory shaft.

16. Driving mechanism as defined in claim 14, and also including manually operable means for moving at least one end of the driving shaft in a direction opposite to that stated so as to render ineffective the power transmitting means at that end of the shaft.

17. In a car structure having a body and running gear including a truck frame and wheel and axle element; driving mechanism for an accessory which is carried by the body and which has an actuating shaft; said mechanism including, a unitary driving shaft and journals therefor, a belt pulley on one end of the shaft, journal mounting arm means pivotally supported on the car body and supporting the shaft journals for swinging of the other end of the driving shaft toward and from the wheel and axle element about an axis transverse of the driving shaft which axis passes approximately through the center of the belt pulley, a belt pulley on the accessory actuating shaft and a driving belt encompassing the two pulleys to transmit power from the driving shaft to the accessory actuating shaft, a power transmitting element carried by the swinging end of the shaft and adapted to be placed in effective power receiving relation to the wheel and axle element by swinging of the shaft in one direction about said axis, and yielding means tending to swing the shaft in said direction about said axis, all whereby the tightness of the driving belt remains substantially constant throughout the swinging movement of the drive shaft.

18. Driving mechanism as defined in claim 17 and in which the power transmitting element on the swinging end of the driving shaft is a traction roller adapted to be placed in tractive engagement with said element by swinging toward said element.

19. Driving mechanism as defined in claim 17, and also including manually operable means for swinging the driving shaft in an opposite direction to render ineffective the power transmitting element carried by the swinging end of the shaft.

20. In a car structure having a body and running gear including a truck frame and wheel and axle element; driving mechanism for an accessory which is carried by the body and which has an actuating shaft; said mechanism including, a belt pulley on the accessory actuating shaft, a unitary driving shaft, a traction roller mounted on one end of the driving shaft, a belt pulley on the driving shaft near the other end thereof and lying in the plane of the first mentioned pulley, a transmission belt drivingly connecting the two pulleys, said driving shaft being mounted on the body for limited swinging movement and in its swinging movement being adapted to move the traction roller into and out of tractive engagement with the wheel and axle element, yielding means applied to the driving shaft for swinging it in a direction to so engage the traction roller with the wheel and axle element, the swinging axis of the driving shaft being located approximately in said pulley-plane whereby the tightness of said driving belt remains substantially constant throughout the described swinging movement of the driving shaft.

21. Driving mechanism as defined in claim 20,

16

and also including manually operable means for swinging the driving shaft in a direction to disengage the traction roller from the wheel and axle element.

5 22. In a car having a body, and running gear including a truck frame and a wheel and axle element; driving mechanism for an accessory which is carried by the car body; said driving mechanism including, a rigid driving shaft, a universal bearing for one end of the driving shaft supported on the car body, a universal bearing for the other end of the driving shaft, means supporting the second mentioned bearing on the truck frame for movement along a line of movement to and from the wheel and axle element, means adapted to transmit power from the wheel and axle element to the second mentioned end of the driving shaft and rendered effective by movement of that end of the driving shaft in one direction along said line of movement, said power transmitting means including a rotary power transmission element which is rotatively fixed on the shaft in axial alignment therewith, means normally urging the second mentioned bearing 10 in said direction, and power transmitting means connecting the first mentioned end of the driving shaft to the said accessory.

23. In a car structure having a body and running gear including a wheel and axle element; 15 driving mechanism for an accessory which is carried by the car body and which has an operating shaft; said driving mechanism including, a driving shaft extending transversely of the car body, a belt and pulley driving connection between the accessory operating shaft and one end of the driving shaft, a traction roller associated with the other end of the driving shaft and adapted to be pressed into tractive engagement with the wheel and axle element, and mounting 20 means for the driving shaft including, an arm pivotally mounted on the car body and carrying at its free end a universally swivelling bearing for the first mentioned end of the driving shaft, yielding means tending to rotate said arm and 25 to move said end of the driving shaft in a direction away from the said accessory operating shaft to tension the belt connecting that shaft with the driving shaft, a transverse mounting shaft journalled on the running gear, an arm fixed to the 30 mounting shaft and carrying at its free end a universally swivelling bearing for the second mentioned end of the driving shaft, yielding means tending to move the last mentioned bearing and its end of the driving shaft toward the running 35 gear wheel, and means connected with the mounting shaft for rotating it to move the last mentioned arm and bearing away from said wheel.

24. In a car structure having a body and running gear including a wheel and axle element; 40 driving mechanism for an accessory which is carried by the car body and which has an operating shaft; said driving mechanism including, a rigid driving shaft extending transversely of the car body, mounting means for the driving shaft on the car structure including a pair of spaced bearings for the shaft, a pair of shaft supporting arms each supportingly connected at one end to one of the shaft bearings, one of said arms being 45 pivotally connected at its other end to the car body and the other one of said arms being independently pivotally connected to the running gear, at least one of said connections of each arm being capable of allowing universal swivelling 50 movement, driving connection between the acces-

75

sory operating shaft and one end of the driving shaft, and driving connection between the wheel and axle element and the other end of the driving shaft including a rotary power transmission element which is rotatively fixed on the shaft in axial alinement therewith.

25. In a car structure having a body and running gear including a wheel and axle element; driving mechanism for an accessory which is carried by the car body and which has an operating shaft; said driving mechanism including, a driving shaft extending transversely of the car body, mounting means for the driving shaft including an arm pivotally mounted on the car body and carrying at its free end a universally swivelling bearing for one end of the driving shaft, yielding means tending to rotate said arm in one direction about its pivot to correspondingly move the associated end of the driving shaft, driving connection between said end of the driving shaft and the accessory shaft which is rendered effective by movement of that end of the shaft in said direction, the mounting means for the driving shaft also including an arm pivotally mounted on the running gear and carrying at its free end a universally swivelling bearing for the other end of the driving shaft, yielding means tending to rotate said arm in one direction about its pivot to correspondingly move the associated end of the driving shaft, and driving connection between the last mentioned end of the driving shaft and the wheel and axle element which is rendered effective by movement of that end of the shaft in said direction.

26. Driving mechanism as specified in claim 25, and also including manually operable means for moving at least one of said arms and its associated driving shaft end in a direction opposite to that stated to render the associated driving connection ineffective.

27. In a car structure having a body and running gear including a wheel and axle element; driving mechanism for an accessory which is carried by the car body and which has an operating shaft; said driving mechanism including, a driving shaft extending transversely of the car body, a belt and pulley driving connection between the accessory operating shaft and one end of the driving shaft, a traction roller associated with the other end of the driving shaft and adapted to be pressed into tractive engagement with the wheel and axle element, and mounting means for the driving shaft including, an arm pivotally mounted on the car body and carrying at its free end a universally swivelling bearing for the first mentioned end of the driving shaft, yielding means tending to rotate said arm and to move said end of the driving shaft in a direction away from the said accessory operating shaft to tension the belt connecting that shaft with the driving shaft, a transverse mounting shaft journaled on the running gear, an arm fixed to the mounting shaft and carrying at its free end a

universally swivelling bearing in which the second mentioned end of the driving shaft is rotatively and slidably carried, yielding means tending to move the last mentioned bearing and its end of the driving shaft toward the running gear wheel, and manually operable means for moving at least one of said arms and its associated bearing in the direction opposite to that in which it is yieldingly urged.

- 10 28. In a car structure having a body and running gear including a truck frame and a wheel and axle element; driving mechanism for an accessory which is carried by the car body and which has an actuating shaft; said driving mechanism including, a driving shaft, a bearing mounting for one end of the shaft supported on the car body and constrainedly movable with relation to the car body along a line of movement to and from the said accessory shaft, a bearing mounting for the other end of the shaft supported on the truck frame and constrainedly movable with relation to the body along a line of movement to and from the wheel and axle element, the two ends of the driving shaft being independently movable along said lines of movement, power transmitting elements adapted to transmit power from the wheel and axle element to the second mentioned end of the driving shaft and from the first mentioned end of the driving shaft to the said accessory shaft, each of which power transmitting means is rendered effective by movement of the respective end of the driving shaft in one direction along the respective line of movement, and means normally urging the two ends of the driving shaft in the directions stated.
- 15 29. In a car structure having a body and running gear including a truck frame and a wheel and axle element; driving mechanism for an accessory which is carried by the car body and which has an actuating shaft; said driving mechanism including, a driving shaft extending transversely of the car body, a bearing mounting for one end of the shaft supported on the car body and constrainedly movable with relation to the car body along a line of movement to and from the said accessory shaft, a bearing mounting for the other end of the shaft supported on the truck frame and constrainedly movable with relation to the body along a line of movement to and from the running gear wheel, the two ends of the driving shaft being independently movable along said lines of movement, a power transmitting traction roller on the second mentioned end of the driving shaft and adapted to tractively engage the wheel and axle element, a belt-and-pulley power transmission between the first mentioned end of the driving shaft and the shaft of the said accessory, and means normally urging the first mentioned end of the driving shaft away from the said accessory shaft and normally urging the second mentioned end of the driving shaft toward the wheel and axle element.
